ABSTRACT

Apparatus and method for forming a long workpiece in which one end of the workpiece is disposed between upper and lower forming saddles while the other end is inserted into a tiltably suspended rotatable gripper. The workpiece is rotated following each forming step and bending of the workpiece is thus avoided.

2 Claims, 3 Drawing Figures

PATENTED OCT 15 1974

3.841.139

METHOD AND APPARATUS FOR THE FORMING OF A LONG WORKPIECE

The instant invention concerns a method for forming or forging a long workpiece in which the workpiece is tiltably secured at one end, while it rests on a lower, fixedly arranged forming saddle and extends beyond the forming saddle with its other end. The workpiece is rotated around its roll axis and is shifted in the direction of its longitudinal extent after each forming process, performed with an upwardly and downwardly movable forming saddle. The instant invention concerns also an apparatus for performing the method.

If one permits one end of the workpiece to freely extend beyond the lower forming saddle during the forming of a long workpiece, e.g., the frontal axle of a truck, this will not only complicate the transport of said workpiece between the two forming phases, but it could cause the extending end-piece to bend to any one side during the forming process. If the workpiece is rotatable at one end around an axis which is perpendicular to the longitudinal extent of the workpiece, i.e., tiltable, but is otherwise fixedly and immovably arranged, this will also result in the bending of the workpiece after each forming phase.

PRIOR ART

In order to prevent such a disadvantage, in prior art methods (Industrie-Anzeiger [Industrial Journal] No. 84, of Oct. 6, 1970, pp. 2,017 to 2,021) a workpiece was gripped at both ends in such a way as to permit it to move downwards over its entire length rectangular to its longitudinal extent. To permit a lowering during the gripping of both ends of the workpiece, which is necessary in the prior art method, is considered to be very uneconomical.

In the above-cited prior art, a further device is disclosed which comprises a press, a manipulator at one side of the press, and a support means at the other side of the press, in which the press is equipped with a fixedly attached lower saddle and a movably arranged upper saddle, and wherein the manipulator is provided with a rod which is suspended therefrom so as to be tiltable and rotatable. In such a device, the bending of a workpiece can be avoided if the gripper is arranged so that it cannot be tilted but can be lowered, and in that also the support means is arranged in a manner to enable the lowering of same.

It is within the scope of the present invention to provide a method of the above-mentioned type in which one end of the workpiece is tiltably arranged so that a bending of the workpiece is avoided, without the need to secure or support the ends of the workpiece in a manner that it can be lowered. It is also within the scope of the present invention to provide a device for the forming of a long workpiece which does not require that the gripper and support means be arranged for downward movement, but which nevertheless prevents the workpiece from being bent during the forming process.

The present invention provides a method of the above-mentioned type in which the end-piece of the bent workpiece which is supported from the bottom is pressed from the top against the bottom support during the forming, and whereby a rotation of the workpiece in the same direction is performed after each forming phase. The rotational angle after each forming phase is

measured in a manner so that the workpiece is corrected downwardly in all stress-directions.

The present invention provides, in addition, a device having a press, a manipulator arranged at one side of the press, and a support means at the other side of the press, whereby the press is provided with a lower saddle which is fixedly arranged, and a movably arranged upper saddle, and the manipulator is equipped with a tiltably suspended rotatable gripper which rotates in the same direction after each forming phase, and wherein a control plate is attached to each forming saddle at the side of the press opposite the gripper.

The workpiece is fixedly inserted into the gripper and rests on the lower saddle. During the process, the two saddles press into the workpiece at equal depths, whereby the center axis of the workpiece above the lower forming saddle is moved downwards at the depth of penetration of one of the forming saddles. If it is considered that the part of the workpiece which is behind the forming saddle is parallelly moved downward during the forming, then a bend develops in the workpiece between the forming saddle and the gripper at the height of the forming saddle. This bend, however, is constantly corrected when the workpiece, straightened after each forming process, is rotated around a respective angle. The bending is caused because the gripper does not permit a parallel displacement of the workpiece axis as a result of the tiltable arrangement.

It is now possible that the end of the workpiece behind the forming saddle will also bend during the shaping due to certain influencing factors, i.e., asymmetric forming saddles. This workpiece end, preferably, is provided with raw measurements over its entire length, whereby the forward feed during the forming at the gripper side is made away from the press. Since the end of the bent workpiece behind the forming saddle cannot be corrected because of the equiaxial rotation, control plates are therefore arranged at this side. Thus the lower control plate, as well as the lower forming saddle, is thereby fixedly arranged, while the upper control plate together with the upper stretching saddle is upwardly and downwardly movably arranged. The control plate level is recessed to a certain extent in contrast to the forming saddle level. During each forming process, the respectively bent workpiece is corrected. The minimum distance of the two plates develops at the moment when the forming saddles have reached the largest penetration-depth into the workpiece. In a case where the workpiece, which is placed between the control plates, is not bent and where the forming or forming saddles have reached their maximum penetration-depth into the workpiece, then each one of control plates is a small distance from the workpiece, so that the respective end of the workpiece cannot exceed a certain extent of bending. This is of special importance since in the case of a larger bending, the turning of the workpiece would no longer be possible.

It is advantageous to start the transforming movement after the turning movement or to perform both movements simultaneously since it is possible that the workpiece is more or less stuck on the lower forming saddle after a forming process. During rotation, the workpiece can be removed from the lower forming saddle without difficulty.

The longer the control plates, the better are the effects of control, i.e., the smaller is the angle of the bend. The ideal length of the control plate is the equal

length of the workpiece behind the forming saddles. For practical reasons, the control plates are, however, shorter than the workpiece.

BRIEF DESCRIPTION OF THE DRAWINGS

A preferred embodiment of the instant invention is shown in the drawing, whereby:

FIG. 1 is a sideview of the press with a manipulator;

FIG. 2 is a view taken along line II—II of FIG. 1, the view looking in the direction of the arrows ; and

FIG. 3 is a view taken along line III—III of FIG. 1, the view looking in the direction of the arrows.

DETAILED DESCRIPTION OF THE INVENTION

The device according to the drawing is equipped with a press 1 of prior art construction having a fixedly attached lower forming saddle 2, and an upwardly and downwardly movable forming saddle 3 which is attached to a piston rod 4. The press 1 is of a prior art construction and is therefore not described here in detail. The two forming saddles 2, 3 are arranged between two side frames 5 of the press of which only one is shown in FIG. 1.

A lower control plate 6 is fixedly attached at the lower forming saddle 2; and an upper control plate 7 is connected to the upper forming saddle 3. The two control plates 6, 7 are of equal length and are arranged above each other, extending in the direction of a long workpiece 8 which is of a rectangular cross-section and rests on the lower forming saddle 2. A free end section 8a of the workpiece 8, which extends beyond the lower forming saddle 2, when bent, rests on the lower control plate 6 during the forming. The control plates 6, 7 are elongated and have a rectangular profile so that their area which contacts the workpiece is level. If the free end of the workpiece 8 is longer than the control plates 6, 7, then only a part of the free end rests on the lower control plate 6.

A manipulator 9 of the prior art design is located at that side of the press 1 which is opposite the control plates 6, 7. The manipulator 9 is equipped with a wheeled carriage 10 which is movable on rails 11. A support 12 is provided on the carriage 10 and is attached to the carriage 10 by means of fish plates 13 at the side away from the press 1, so that it is rotatable or tiltable about an axis 14, perpendicularly to the longitudinal extent of the workpiece 8. On the side of the manipulator 9 which is facing the press 1 are provided spring means 15 between the carriage 10 and the support 12. The spring means 15 are lockably constructed so that the finished workpiece can be retained in a horizontal position during its removal.

A gripper-support tube 16 is rotatably positioned and horizontally arranged in the support 12. The rotation of the gripper-support tube 16 is activated by means of a motor 17 via gears 18, 18a, with said motor being mounted on the support 12. The gripper-support tube 16 extends from support means 12 towards press 1 and carries a gripper 19 which is activated by a mechanism 20 which is provided at the side of support means 12 opposite the gripper 19. The device 20 activates the gripper 19 by means of rods (not shown in the drawing) which are arranged in the gripper-support tube. A gripper-support tube which is rotatably arranged in a support means 12, having a gripper activatable by means of rods which are arranged in a gripper-support tube,

is known in the prior art (German Pat. No. 1,202,111), so that a more detailed description of the means for rotating and activating the gripper is not necessary.

With the beginning of the forming of the workpiece 5, the manipulator 9 is positioned near the press 1 and the gripper 19 is near the saddles 2, 3. At the start of the entire forming operation, the largest part of the workpiece is located on that side of the forming saddles 2, 3 which is opposite the gripper 19. This means, that on the side of the gripper, there is only one very short section of the workpiece, while on the other side, there is located a very large section of the workpiece. The first forming phase begins when the upper forming saddle 3 moves downwards. After the upper saddle 3 has again moved upwards, the gripper 19 is rotated by 90° by means of motor 17, so that the workpiece retains its rectangular profile during the forming. The gripper 19 is then moved one step away from the press 1. The next forming phase can now follow.

The displacement movement of the gripper can be made in a manner whereby only the carriage is moved gradually. It is, however, also possible to permit the carriage to roll away from the press at a constant speed, whereby the gripper remains in the area during a forming phase and moves one step away from the press after each forming process. The gradual rotating and moving of the gripper can be controlled by means of a suitable control device in dependency on the movement of the upper forming saddle. It is also possible to use a suspendedly arranged manipulator in place of a manipulator moved on the ground.

It is claimed:

1. An apparatus for the forming of a long workpiece comprising a press having upper and lower forming saddles, the lower saddle being fixedly mounted, the upper saddle being movable in an upward and downward direction relative to the lower saddle, a manipulator arranged on one side of the press, the manipulator being provided with a rotatable gripping member for gripping and rotating a workpiece, means mounting the gripping member for tilting movement about a horizontal axis, whereby a parallel displacement of the workpiece axis during the forming is not possible and the workpiece, during each forming step, obtains a bend between the grip end and the saddles, means pushing the workpiece gradually forward between the saddles so that a bend which has developed during one forming step is corrected during a consecutive forming step with the rotation of the workpiece always being made in the same direction thereby effecting a corrective straightening force on the bent workpiece during each forming step, and support means for the workpiece on the opposite side of the press, the support means including a control plate attached to each saddle.

2. An apparatus for the forming of a long workpiece comprising a press having upper and lower forming saddles, the lower saddle being fixedly mounted, the upper saddle being movable in an upward and downward direction relative to the lower saddle, a manipulator arranged on one side of the press, the manipulator being provided with a rotatable gripping member for gripping and rotating a workpiece and which is capable of upward and downward tilting movement, whereby a parallel displacement of the workpiece axis during the forming is not possible and the workpiece, during each forming step, obtains a bend, means effecting relative

longitudinal movement between the workpiece and the saddles so that a bend which has developed during one forming step is corrected during a consecutive forming step with the rotation of the workpiece always being made in the same direction thereby bringing about a corrective straightening force on the bent workpiece

during each forming step, and support means for the workpiece on the opposite side of the press, the support means including a control plate attached to at least the upper saddle.
